FIG. 1

FIG. 2

FIG. 3

FIG. 4

FIG. 5

FIG. 6

FIG. 7

FIG. 8

FIG. 1 is a left side elevation view of a table fork showing my new design and illustrates the tines curving forwardly past the plane of the handle.

FIG. 2 is a front elevation view of the table fork in FIG. 1 and illustrates different width and taper of the tines.

FIG. 3 is a right side elevation view of the table fork in FIG. 1.

FIG. 4 is a back elevation view of the table fork in FIG. 1.

FIG. 5 is a view, partly in cross section, taken along section line 5—5 of FIG. 2 and illustrates the tines extend forwardly past the plane of the handle.

FIG. 6 is a bottom view of the table fork in FIG. 1.

FIG. 7 is a plan view of the table fork in FIG. 1.

FIG. 8 is a perspective view of the table fork in FIG. 1.

The characteristic features of the design reside in a table fork having the configuration shown, and wherein the tines are of different widths and lengths and have different tapers so that the spaces vary therebetween. The tines are curved backwardly relative to the handle along a length adjacent the handle and forwardly of its plane along substantial free end portions of the individual tines.

I claim:

The ornamental design for a table fork, as shown and described.
